CATHODE RAY TUBE

Max Knoll, Berlin, Germany, assignor to Tele-funken Gesellschaft für Drahtlose Telegraphie m. b. H., Berlin, Germany, a corporation of Germany

Application August 4, 1934, Serial No. 738,433
In Germany August 2, 1933

1 Claim. (Cl. 250—162)

This invention relates to cathode ray tubes and more particularly, to method and means of shielding deflecting electrode structures provided within such tubes.

5 The invention is predicated upon this consideration and fact that in Braun tubes having a fluorescent screen having a diameter that is comparatively large compared with the length of the deflected cathode ray pencil as required for television reception, the electrical fields which are set up between pairs of deflector plates themselves or between one deflecting plate and the metallic layer coating the tube wall, occasion an acceleration of the cathode rays which has a 10 different value for each point of the picture. The consequence is that the spot will not appear to be of constant size for all points or places upon the screen usually disposed at right angles to the tube axis.

20 To preclude this drawback, the deflector plates and/or the screen according to this invention should be arranged in a way as hereinafter to be described. The said difficulty can be avoided also by the circuit arrangement of the deflector plates.

25 In the drawing Figure 1 shows plan and elevation views of an electrode system embodying my invention. Fig. 2 shows a plan and elevation view of a modification of the embodiment shown in Figure 1.

30 Referring to Figs. 1 and 2 the deflector plate pairs are designated by 10 and 11. Between these is mounted a diaphragm 12 having an oblong aperture 12 which is in conductive connection with the metallic lining 13 of the tube. The 35 force lines of the electrical field which, in the absence of the diaphragm 12 would arise, on the one hand, between the deflector plate pair 10 and the plate pair 11, on the other hand, in an arrangement as shown in Fig. 1, terminate on the diaphragm 12 so that only a minor portion thereof will traverse through the space passed by the cathode ray pencil. In other words, by the

provision of the diaphragm 12 the influence of the said field upon the speed of the cathode ray pencil, as a matter of fact, is lessened.

Another means to eliminate the said lack of sharpness consists in that protective electrodes are disposed in the vicinity of the deflector plates, for example, in a way as shown in Fig. 2. These protective electrodes 14 are at an invariable and lower potential in reference to the tube wall than the deflector plates, preferably at the very 10 potential of the tube walls.

The said drawbacks of the earlier Braun tubes will also be reduced by that the deflector plates are impressed with such a constant biasing potential that, at maximum deflector potential, one plate is made about as positive as the other one is negative in reference to the tube wall. The same thing is attainable if the source of the deflector voltage is conductively connected in its electrical midpoint with the wall of the tube. 20

In conjunction with the means disclosed, or else independently thereof, the said effect of the lack of sharpness may be avoided by that the surface of the fluorescent screen is inclined in reference to the plane at right angles to the tube 25 axis. This inclination should be chosen in such a way that the particular corner of the screen which the cathode ray pencil reaches if the maximum deflection voltage is applied to the two pairs of deflecting plates, will be at the greatest distance. 30

Having thus described the invention, what I claim is:

A cathode ray tube comprising an envelope, a conductive coating upon the inner wall of said envelope, deflecting electrodes within said envelope, cylindrical shield electrodes lying adjacent to and in the same plane as the deflecting electrodes, and electrically conductive connections between said shield electrodes and the conductive coating. 35 40

MAX KNOLL.
